POCKET POWDER-CASE

Franz Anderl, Vienna, Austria, assignor to Frida Weissenbeck, Vienna, Austria

Application July 27, 1935, Serial No. 33,587
In Austria August 7, 1934

1 Claim. (Cl. 240—6.45)

This invention relates to a novel type of pocket powder-case equipped with self-contained lighting means for the purpose of illuminating the face of the user thus enabling the case to be used in the dark. In accordance with the invention the preferably box-shaped powder-case is furnished at one edge with a reflector adapted to receive an incandescent lamp and to be rotatable in a manner known per se, which reflector is also adapted to coact with arresting means on the hinged lid of the case in two positions disposed at about 180° to each other. In this manner the possibility is provided of using the case, when closed, as an ordinary pocket lamp. The reflector may be extended towards one side, and designed to serve as a container for the reception of a lip-stick or the like.

A form of construction embodying the invention is shown by way of example in the accompanying drawing, in which:

Fig. 1 shows in perspective the powder-case according to the invention, with hinged-up lid, and hinged up powder holder.

Fig. 2 is a plan view partly in section.

Fig. 3 is a side elevation, partly in section.

Fig. 4 shows a detail.

Referring to the drawing, the box-shaped case is provided with a lid 2 hinged along one longitudinal side of the case and fitted with mirror 3, and is equipped with a likewise hinged powder receptacle 4. At the sides of the case there are stowed the dry cells 5 and 6 which are connected together in series by the yoke 7 insulated from the casing. The one edge of the case is of tubular shape, to provide a casing 8 for the reception of the rotary reflector 9. Into this reflector 9 there is inserted the holder 10 for an incandescent lamp 11, which holder is adapted to engage in the said reflector 9 when inserted therein. A milled edged head 12 on the lamp holder permits of convenient rotation by hand of the reflector together with the incandescent lamp. The extension 13 of the reflector can serve the reception of a tubular container 14 for a lip-stick or the like. The container 14 is likewise

provided with a milled edged head 15 for the purpose, on the one hand, of facilitating rotation of the reflector in cooperation with the head 12, and on the other hand to permit of withdrawal of the container with the lip-stick or the like. The holder 10 of the lamp consists of an insulating portion 16 made for example from wood, and of a contact member 17 which is connected to the one pole of the incandescent lamp, and which, in the switched on position, coacts 10 with the pole piece 18 of one of the dry cells, while the second pole of the dry battery is connected through the yoke 7 to the opposite pole of the other dry battery 5 of which the other pole constituting the outer shell is conductively 15 connected to the metal casing part 8 to complete the circuit. On the lid 2 of the case 1 there is provided a double catch 19 which in the one position of the reflector notch 20 of the catch coacts with the edge 21 of the rotary reflector, and 20 in another position of the reflector notch 23 of the catch engages the edge 22 of the reflector, thereby holding the lid closed with the reflector open towards the outside, and permitting of the use of the powder-case as an ordinary pocket 25 lamp. The contact member 17 is made so long that the lamp is fed with current in any position of the reflector within two positions of the reflector approximately 90° apart, whereas in all other positions the pole 18 of the battery rests 30 against the insulating wooden socket 16, as is shown more particularly in Fig. 4. The rotary movement of the reflector is limited by the provision of a nose 24.

I claim:

In a powder-case having a hinged lid a rotary reflector mounted at one edge of the case, an incandescent electric bulb and holder mounted in the said reflector, cells for supplying current to the said bulb stowed in the said case, and detent 40 means on the said lid for the arrestment of the said reflector in two positions disposed approximately 180° apart, the circuit of the bulb being closed in one of said positions.
